[57] CLAIM

The ornamental design for a tower guillotine cigar cutter, as shown and described.

DESCRIPTION

FIG. 1 is a right front perspective view of the first embodiment of a tower guillotine cigar cutter showing my new design;

FIG. 2 is a left rear perspective view thereof;

FIG. 3 is a top plan view thereof;

FIG. 4 is a right side elevational view of the second embodiment shown with an alternative box base, the opposite side being a mirror image with the exception of the cord; and,

FIG. 5 is a front view of the second embodiment.

The second embodiment differs from the first only by the box base configuration. The bottom views of both embodiments are flat and unornamented.
